UNITED STATES PATENT OFFICE.

JOHN W. CLOSE, OF BUFFALO, NEW YORK.

ROTARY SNOW-CLEARER FOR RAILWAY-TRACKS.

SPECIFICATION forming part of Letters Patent No. 225,917, dated March 30, 1880.

Application filed November 28, 1879.

To all whom it may concern:

Be it known that I, JOHN W. CLOSE, of Buffalo, in the county of Erie and State of New York, have invented certain new and useful Improvements in Rotary Snow-Clearers for Railway-Tracks and other Roadways; and I do hereby declare that the following is a full, clear, and exact description of the invention, which will enable others skilled in the art to 10 which it appertains to make and use the same, reference being had to the accompanying drawings, and to the letters of reference marked thereon, which form a part of this specification.

15 Figure 1 is a vertical central longitudinal section of my improved snow-clearer on line *yy* of Fig. 2. Fig. 2 is a front elevation, partly in section, on line *xx* of Fig. 1. Fig. 3 is a side elevation of the snow chamber or receptacle. Fig. 4 is a front-edge view of one of the hollow arms or buckets and its hollow shaft.

20 The same letter indicates the same part wherever it occurs in the drawings. The nature of my invention consists in the removal of snow from a track or roadway by means of an apparatus which, as it gathers the snow, melts it by the application of steam or other heat, and throws it in a wholly or partially melted condition to the side of the roadway or track.

25 It consists more specifically in providing a track-clearer with a snow-receptacle having hollow walls for the reception and conveyance of steam and its injection among the snow, and with rapidly-rotating hollow perforated arms or buckets, which also receive steam and diffuse it through the snow, and by the velocity of their rotation throw the wholly or partially melted snow out of the snow-chamber.

30 In the accompanying drawings, which clearly represent the invention, *A* marks the base-plate, which may be provided with wheels or runners, as preferred, to adapt it to propulsion on a railway-track or common road. For railway use it is placed in front of the locomotive and is propelled by it as snow-plows usually are. The boiler of the locomotive supplies the steam which is used in the apparatus. On 35 the forward end of the base-plate is placed a cylindrical snow receptacle or chamber, *B*,

open in front and provided with a broad scoop or shovel, *L*, which lifts the snow from the track and guides it into the cylinder *B*.

Any suitable braces *C* hold the cylinder in 55 place. The walls of the cylinder are made hollow, having on all sides the steam-space *D*, which is connected with the source of steam-supply by the steam-pipe *E*. This pipe is journaled at *I J*, and serves as the shaft of the 60 hollow arms or buckets *F*, which are attached to its forward end. There is a free passage for steam from pipe *E* into the arms *F*, and these are perforated with numerous holes *h*, which allow steam to escape into the cylinder 65 *B*. The cylinder-walls also have numerous perforations for the same purpose.

The hollow shaft *E* receives rotation from any suitable mechanism operated by the locomotive, and here represented by the crank *G*. 70

75 *H* marks an additional induction steam-pipe to supply steam from an additional locomotive, should it prove desirable. As during a snow-blockade the locomotives are not in use in transporting trains, any reasonable number of them would be available for the purposes of this invention, and steam could be led from them to the cylinder *B* through flexible hose.

In the upper side of receptacle *B* is an opening, *M*, through which the wholly or partially melted snow is thrown by the buckets or arms *F*. These arms have a slight twist to facilitate their penetration of a snow-bank.

80 To prevent the too rapid condensation of the steam in the steam-space *D*, I line its walls 85 with wood or other non-conductor, *l*. If burning petroleum is to be used, the lining should be of baked clay or other non-combustible material.

85 Should the heat from the injected steam not 90 prove sufficient to melt the snow with the required rapidity, I contemplate the use of an oil-fire applied from the tank *M'* below the cylinder *B* to heat that cylinder. I also contemplate the injection of burning petroleum 95 among the snow to supplement the action of the steam when required.

100 The operation of the machine is obvious from its construction. As it is pushed along the track by the locomotive it collects snow in the cylinder *B*, rapidly melts it, and throws it, in a fluid or semi-fluid condition, to the side of

the track by the rapid revolution of the arms or buckets F. Any desired number of these arms may be attached to the shaft E.

When the invention is applied to common roadways, special means of propulsion and special sources of steam-supply must be provided; but they form no part of my present invention.

Having thus fully described my invention, 10 what I claim as new, and desire to secure by Letters Patent, is—

1. A snow-clearer having perforated hollow walls, connected with a source of steam-supply, and perforated hollow revolving arms, which 15 are caused to rotate in the snow-chamber to assist in melting the snow and to throw it out of the machine to one side of the road or track, all substantially as specified.

2. In a snow-clearer, the combination of a 20 stationary chamber or snow-receptacle provided with hollow walls heated by steam, and

perforated so as to inject steam through the snow, with hollow perforated arms, also heated by steam, and injecting steam through the snow and revolving to throw it out of the same, 25 all substantially as specified.

3. In a snow-clearing machine, hollow perforated steam-arms, supplied with steam from any suitable boiler by means of a hollow shaft and caused to rotate by suitable mechanism, 30 in combination with a snow-chamber in which the snow is wholly or partially melted and from which it is thrown out by the centrifugal action of the revolving arms, all as set forth.

In testimony that I claim the foregoing as 35 my own invention I affix my signature in presence of two witnesses.

J. W. CLOSE.
